SASH GUIDE AND CUP UNIT

Glenn B. Haas, Oak Harbor, Ohio, assignor to
Defiance Metal Weatherstrip Company, Oak
Harbor, Ohio, a corporation of Ohio

Application July 31, 1947, Serial No. 765,042

1 Claim. (Cl. 20—11)

1

This invention relates to building structures, and in particular to means and methods for securing cups in window sash guides, such cups being used, for example, to accommodate fasteners employed in securing the sash guide to the window frame.

One object of this invention is to provide a simple yet effective means and method for securing a cup in an aperture in a sash guide, this being inexpensive as well as adapted to mass production methods.

Another object is to provide a sash guide having a cup secured in an aperture thereof by forming projections in the walls of the cup immediately behind the rim of the aperture, thereby anchoring the cup firmly to the sash guide.

Another object is to provide an improved means and method of securing a cup in an aperture in a sash guide, wherein the cup is provided with a flange engaging the rim of the aperture and is also provided either with a projection or a ridge on the opposite side thereof from the flange so as to anchor the cup relatively to the rim of the aperture.

Another object is to provide an improved means and method of securing a flanged cup in an aperture in a sash guide, wherein the edge of the aperture is provided with an inwardly-extending flange which tightly grips the side walls of the cup with a press fit.

Another object is to provide an improved means and method of securing a cup in an aperture in a sash guide, wherein the edge of the cup and the edge of the aperture are interlocked and upset so that they are firmly anchored to one another.

In the drawings:

Figure 1 is a front elevation of a portion of a window sash guide with a cup secured therein, according to a preferred form of the invention;

Figure 2 is a side elevation, partly in central vertical section, of the sash guide and cup shown in Figure 1;

Figure 3 is a horizontal section along the line 2—3 in Figure 2;

Figure 4 is a vertical cross-section along the line 4—4 in Figure 2;

Figure 5 is a vertically-inclined longitudinal section taken along the line 5—5 in Figure 1;

Figure 6 is a front elevation of a cup used with the sash guide shown in Figures 1 to 5 inclusive;

Figure 7 is a side elevation of the cup shown in Figure 6;

Figure 8 is a diagrammatic vertical section through a sash guide and machine for securing

2

the cup to the sash guide in the manner shown in Figures 1 to 5 inclusive, prior to the commencement of the securing operation;

Figure 9 is a fragmentary view of a central portion of Figure 8 by showing the positions of the parts during the securing operation;

Figure 10 is an enlarged fragmentary vertical section of a modified sash guide and cup structure;

Figure 11 is a fragmentary side elevation, partly in vertical section, of a further modified sash guide and cup structure; and

Figure 12 is a fragmentary vertical section through a still further modified sash guide and cup structure.

Referring to the drawings in detail, Figures 1 to 3 inclusive show a sash guide and cup structure, generally designated '0, according to a preferred form of the invention, as consisting generally of a sash guide 11 having a cup 12 secured in an aperture 13 therein. The sash guide 11 is employed in windows having a sliding sash, and is secured to the window frame 14 by fasteners 15 received in the cups 12, only one of which is shown. The sash guide 11 is roughly in the form of a channel member having a central groove 16 for slidably receiving the window sash, the groove 16 being provided with side walls 17 and a bottom wall 18, the latter, in turn, being provided with recesses or countersunk portions 19 surrounding the apertures 13 (Figure 3). The countersinks or recesses 19 are provided for the purpose of receiving the edge flange 20 of the cup 12 so that the flange 20 will be flush with the bottom wall 18 of the sash guide groove 16.

The cup 12 is of approximately cylindrical shape, and is provided with side walls 21 and a bottom wall 22, the latter having a hole 23 for the passage of the shank of the fastener 15.

The cups 12 are preferably stamped out of sheet metal by means of dies, but may be formed in any other manner.

The sash guide 11 on opposite sides of the guide groove 16 is provided with front walls 23 and side walls 24. The latter terminate in bent portions 25 which engage the adjacent surface 26 of the window frame 14. The fasteners 15 thus hold the portions 25 against the surface 26 (Figure 3). The cups 12 serve to hold the heads of the fasteners 15 below the level of the guide groove 16 so as to avoid any possibility of interference with the sliding of the sash in the sash guide 11.

In order to secure the cup 12 in the aperture 13 of the sash guide 11, the cup 12, after its inser-

tion in the aperture 13, is provided with protuberances or projections 27 (Figures 3, 4 and 5) which are formed by forcing the material of the side walls 21 outward behind or beneath the bottom wall 18 of the guide groove 16. As the sash guide 11 and cups 12 are ordinarily made of metal this means and method of securing the two together is simple and effective.

In order to secure the cup 12 within the aperture 13 of the sash guide 11 (Figure 8) the assembly of the cup 12 and sash guide 11 is inverted and placed in a special forming fixture or machine, generally designated 30 (Figures 8 and 9) with the bottom walls 18 of the guide groove 16 resting upon the upper surface or anvil 31 of the machine 30. The latter is provided with a base 32 having a recess 33 therein closed by a cover plate 34 which carries the anvil surface 31. The cover plate 34 is also provided with an aperture 35 of slightly smaller diameter than the diameter of the flange 20, so as to support the latter in the position shown in Figures 8 and 9.

Reciprocably mounted in the recess 33 is a pair of oppositely-facing L-shaped plungers 36, the horizontal portions 37 of which are urged toward one another by coil springs 38 abutting the end walls 39 of the recess 33. A stop 40 mounted in a slot 41 midway between the end walls 39 prevents the vertical portions 42 of the plungers 36 from touching one another and leaves a gap 43 between them. The gap 43 flares outward at its top (Figure 8) due to the fact that the inner edges of the top portions 42 are bevelled off as at 44 in opposite directions. The vertical portions 42 are also provided with outwardly-facing rounded projecting ends 45 which, during the operation of the machine 30, serve to form the projections or protuberances 27 which lock the cups 12 in engagement with the sash guides 11.

In order to accomplish this, the machine 30 is mounted on the bed 46 (Figure 8) of a press or similar machine (not shown) having a vertically-reciprocating plunger 47 provided with a tapered lower end 48. The plunger 47 is of a small enough diameter to pass through the opening 23 in the cup 12, and its tapered end 48 is inclined similarly to the bevelled portions 44 of the horizontally-moving plungers 36.

In the operation of the machine 30 and the process of this invention, a cup 12 is inserted through one of the apertures 13 in the sash guide 11 and the latter is then inverted (Figure 8) with the flange 20 of the cup 12 resting on the rim of the aperture 35 in the cover plate 34 of the machine 30. The vertical portions 42 of the horizontally moving plungers 36 thus extend upward within the cup 12 and their outwardly-projecting ends 45 lie in a higher level than the countersunk portions 18 surrounding the apertures 13.

The press is then operated to cause the plunger 47 to move downward through the hole 23 so that its tapered end 48 engages the bevelled portions 44 of the vertical plunger arms 42 and forces them apart (Figure 9). When the rounded ends 45 engage the side walls 21 of the cup 12, they push these side walls 21 outward, forming the projections or protuberances 27. While this is occurring, the rim of the aperture 13 serves as an abutment to prevent the adjacent portion of the cup 12 from being likewise forced outward. The result is that the protuberances 27 firmly lock the cup 12 to the sash guide 11, with the countersunk portion 18 firmly locked between the flange 20 and the projections or protuberances 27. The plunger 47 is then retracted upward (Figure 8),

whereupon the coil springs 38 return the plungers 36 to their positions in engagement with the stop 40, and permit the assembly 10 of the cup 12 and sash guide 11 to be withdrawn from the machine 30.

Since it is contemplated that the projections or protuberances 27 will be formed in pairs at diametrically opposite positions in the side walls 21 of the cups 12 (Figures 1, 3 and 4), the ends 45 of the vertical portions 42 of the plungers 36 are preferably bifurcated or in pairs in order to produce two protuberances 27 simultaneously side by side.

The modification shown in Figure 10 employs 15 a cup 50 similar to the cup 12 used in the form of the invention shown in Figures 1 to 9 inclusive, but the sash guide 51 has an inwardly-extending cylindrical flange 52 forming a cylindrical bore 53 in place of the aperture 13. The diameters 20 of the bore 53 and cup 50 are so chosen that it is necessary to employ a considerable pressure to force the cup 50 into the bore 53 with the cup 25 flange 54 resting against the countersunk portion 55 of the sash guide 51. This press fit of the cup 50 with the flange 52 of the sash guide 51 is preferably accomplished in a conventional press (not shown) of any suitable type. The cup 50 is thus held by frictional engagement with the flanged portion 52 of the sash guide 51.

The modification shown in Figure 11 is somewhat similar to that shown in Figures 1 to 9 inclusive in that the cup 60 is held in engagement with the sash guide 61 by pushing the side walls 62 of the cup 60 outward. In place of the projections 27, however, an annular projection 63 is formed on the opposite side of the countersunk portion 64 from the cup flange 65. This may be accomplished by making the projections 45 of the machine 30 (Figure 8) of semi-circular form so 30 that the two halves in assembly form a circular die, the halves of which are forced outward by the plunger 47, thus forming the annular projection 63. The operation of forming the annular projection 63 is otherwise similar to the operation 35 of forming the projections 27 as previously described, hence requires no duplication of description.

The modification shown in Figure 12, the cup 50 is united with the countersunk portion 71 of 50 the sash guide 72 by crimping the flange 73 of the cup 50 around the outwardly-flanged portion 74 surrounding the aperture 75 into which the cup 50 is inserted. In this modification (Figure 55 12), the crimping operation causes the outer portion 76 of the flange 75 to be turned outward parallel to the countersunk portion 71, and the edge portion 77 of the cup flange 73 to be turned rearward around the edge of the outwardly-extending portion 76 and with its rim portion 78 turned inward around the same portion 76. The above-mentioned flange portions 73 and 74 are therefore interlocked with an overlapping grip, this likewise being done in a crimping die (not shown).

65 What I claim is:

A sash guide and cup unit for receiving a fastener securing said unit to a window frame, said unit comprising a sash cup having an annular edge flange and a substantially flat bottom with 70 a hole therein for receiving said fastener, and an elongated longitudinally-grooved sash guide member having an aperture in the grooved portion thereof of substantially the size of said cup and having a countersink surrounding the edge 75 of said aperture, said countersink having a width

and depth corresponding respectively to the width and thickness of the cup edge flange, said cup being disposed in said aperture with its edge flange seated in said countersink, said cup having a plurality of outwardly-projecting protuberances disposed across from one another adjacent said sash guide and on the opposite side of said sash guide from said countersink and flange.
